United States Patent Office.

JOHN L. MASON, OF NEW YORK, N. Y.

Letters Patent No. 81,919, dated September 8, 1868; antedated August 27, 1868.

IMPROVED GARBAGE-BOX.

The Schedule referred to in these Letters Patent and making part of the same.

TO ALL WHOM IT MAY CONCERN:

Be it known that I, JOHN L. MASON, of the city, county, and State of New York, have invented a new and useful Improvement in Garbage-Boxes; and I declare hereby that the following is a full, clear, and exact description thereof, which will enable those skilled in the art to make and use the same, reference being made to the accompanying drawing, forming part of this specification, in which—

Figure 1 represents a perspective view of this invention when the box is raised.

Figure 2 is a similar view when the box is down.

Figure 3 is a section of the same.

Figure 4 is a detached view of the handle.

Similar letters indicate corresponding parts.

My apparatus consists, first, of a receptacle or receiver, R, of a nearly cylindrical form. I prefer it to be largest at the bottom, resting on a plate of cast iron or other material, flush with and making part of the surface of the sidewalk, and as near to the outer edge of the sidewalk as may be, without interfering with the passage of vehicles. I sometimes raise the middle of the plate or flag-stone above the level of the sidewalk, for the centre of the bottom of the receptacle to rest upon. If desirable, there may be an opening in the sidewalk for the receiver to sink into.

This receptacle has a tightly-fitting bottom hinged to it in any known way, but I prefer to connect it so that it will move perpendicularly to the axis of the receptacle when opened or closed.

The receptacle has also a tight-fitting cover, hinged in any way, but I prefer it to move, in opening and closing, in the way I have suggested for the bottom, perpendicular to the axis of the receptacle.

The bottom and cover have their proper fastening around the bottom of the receptacle, and a groove is provided, leading to the gutter, for any slight leakage that may occur.

This receptacle is connected by a strong arm, A-A, with a vertical slide, S, operated by a pinion, p, for raising or lowering the receptacle.

This slide and pinion are enclosed in a hollow cylindrical column, P', which is supported by a post, P, extending into the ground, or into masonry of sufficient stability and strength to sustain it firmly in the performance of its duty. This post should be placed as near to the outer edge of the pavement as the free passage of vehicles will permit.

The post P is hollow, and it receives the column P', which is allowed to revolve in the post P.

In the interior of the column P' is fitted the slide S, which is provided with a toothed rack, that gears in the pinion p, secured to a shaft that has its bearings in the column P', and is turned by a handle, k.

The arm A of the receptacle R is rigidly attached to said slide, and when the pinion p is rotated, so as to raise or lower the slide, the arm A moves in a slot in the column, and the receptacle R is also raised or lowered.

The handle k ought to be so constructed that it can be readily taken off, so that the garbage-gatherer is enabled to carry the same from one post to the other.

When the receptacle is to be emptied, the garbage-gatherer raises the same by turning the pinions p, and then he swings the receptacle out over the cart, as shown in fig. 1, by turning the column P' in the post P.

When the receptacle has thus been brought in the proper position, its bottom is turned off, and the garbage is dumped into the cart.

After the receptacle R has thus been emptied, it is lowered to its proper place, ready to receive a fresh supply of garbage.

Having thus described my invention, what I claim as new, and desire to secure by Letters Patent, is—

1. The rising and falling slide S, in combination with the garbage-receptacle R, constructed and operated as and for the purpose described.
2. The revolving-column P', in combination with the slide S and receptacle R, constructed and operated as and for the purpose set forth.

JOHN L. MASON.
